BRUSH HAVING BRISTLE CLEANING APERTURES

Frederick J. Marco, Des. Plaines, Ill.

Application May 4, 1949, Serial No. 91,263

9 Claims. (Cl. 15—167)

1

My present invention relates to improvements in brushes.

The primary object of my invention is to provide a brush having a head in which a plurality of tufts of bristles are mounted, and which head is further provided with a plurality of apertures of a character enabling the efficient cleaning of the tufts of bristles.

My invention in the main is concerned with the provision of a brush of the character indicated having unique application for the aforementioned purpose. Essentially, I propose to provide a plurality of apertures in the head of the brush, in which each aperture is characterized in the main by having the defining wall thereof of conical formation and spirally grooved as to impart a swirling or rotating movement to water applied in a stream against the brush head so that the water is thrown out by centrifugal force upon the roots of tufts of bristles to bathe the latter. Further, in order to utilize the vortex created at the throat to thoroughly cleanse the roots of the tufts of bristles, the opening of the apertures at the bottom surface of the head of the brush from which the tufts of bristles extend outwardly, are preferably flared or rounded so that, in addition, surface tension or capillary action of water with such a surface further effects delivery of the water in a swirling outward expanding fashion to the roots of the tufts of bristles.

A preferred feature of one embodiment of my invention is to provide apertures having the defining surfaces thereof, lying substantially in the surfaces in a pair of cones, one extending inwardly of the top and bottom surfaces of the head with the apices of such cones directed toward each other, and in which the defining walls of the apertures are spirally grooved for the purpose above indicated.

My invention may also be embodied in a construction in which the apertures have the defining walls of each thereof lying in the surface of the cone and spirally grooved, and in which the apex of the cone is directed toward the top surface of the head of the brush. Additionally, if desired, the openings of such apertures at the bottom surface of the cone may be flared toward the roots of the tufts of bristles to achieve the additional advantage of surface tension or capillary action of the water as above indicated.

Still further my invention may be embodied in a brush in which the apertures each have the defining wall thereof lying substantially in the surface of a cone and spirally grooved, but in

2

which the apex thereof extends toward the bottom surface of the brush.

In adapting my invention for use, for example, in a tooth brush, two lengthwise extending rows of tufts of bristles may be provided together with three rows of apertures of any of the forms above indicated with each row of tufts of bristles being arranged between adjacent rows of apertures.

Alternatively, if desired, and particularly in instances where a greater number of tufts of bristles is desired, the brush may comprise three rows of tufts of bristles and two rows of apertures of the character indicated with the rows of apertures aligned one each between adjacent rows of the tufts of bristles.

The above and other objects and advantages of my invention will appear from the detail description.

Now in order to disclose fully my present invention I shall describe in connection with the accompanying drawings certain preferred embodiments of my invention.

In the drawings:

Figure 1 is a perspective view of a toothbrush in which my present invention is embodied;

Figure 2 is an enlarged plan view of a portion of the head of the toothbrush of Figure 1;

Figure 3 is a detail vertical sectional view taken substantially along the line 3—3 of Figure 2 looking in the direction indicated by the arrows;

Figure 4 is a detail vertical sectional view showing further embodiment of my invention;

Figure 5 is another detail vertical sectional view showing still another modification of my invention;

Figure 6 is a plan view of the head of a toothbrush illustrating the manner in which a plurality of rows of tufts of bristles and apertures may be embodied in a toothbrush; and

Figure 7 is a plan view similar to Figure 6 but showing another arrangement of tufts of bristles and apertures suitable for use in a toothbrush.

Referring now to Figure 1 of the drawings I have shown a brush 1 of the general configuration of a conventional toothbrush and having a handle 2 and a head portion 3. The head portion 3 comprises a top surface 4 and a bottom surface 5, preferably connected by rounded edge portions. A plurality of tufts of bristles 6 are mounted in a conventional way in the head member 4 with the tufts of bristles projecting outwardly of the bottom surface 5.

In the preferred form of my invention shown

in Figure 3 it will be observed I provide a plurality of apertures 7 in which the defining walls of each thereof is substantially conical form. The apertures 7 each preferably comprise a pair of substantially conical surfaces indicated generally at 8 and 9, arranged with the apices thereof extending toward each other as to provide a reduced throat 10 for the aperture. The substantially cone defining walls 8 and 9 are spirally grooved as indicated at 11. Preferably the apertures at the portions opening into the top and bottom surfaces 4 and 5 are flared or rounded as indicated at 14, for a purpose to be described. Flaring of the opening of the apertures at the top surface is not critical but such flaring at the bottom surfaces as will appear enables the effective cleaning of the tufts of bristles 6.

In the construction described upon disposal of the head 3 below a stream of water, as by holding the head below a faucet, the water enters the aperture 7 and due to the spiral grooving 11 thereof a rotating or swirling action is imparted to the water. The throat 10 of each aperture defines the maximum opening for the passage of water therethrough, and the spiral grooves 11 serve to prevent the stream of water being impinged upon the head from passing straight through the apertures by virtue of the vortex created. The spiral grooves 11 serve to maintain appropriate flow of water for passage through the minimum diameter of the aperture defined by throat 10. In the passage of the water through the lower conical openings 9 of the apertures, the water follows a path gradually increasing in diameter so that substantial centrifugal force is developed, whereupon as the water leaves the apertures at the bottom wall 5 of the head 3 it is thrown against the roots of the tufts of bristles 6. The water thus discharged is effective to cleanse thoroughly the tufts of bristles. The aforesaid flaring of the openings of the apertures at the bottom surface of the head additionally serve, due to surface tension or capillary action of the water with respect to such flared surfaces, for effecting delivery of the water to the roots of the bristles and which together with the rotary motion imparted thereto by the spiral grooves creates a vortex effective in substantial measure to apply the cleansing water to the roots of the bristles to clean same. In addition to cleaning the bristles the above described movement of the water removes any sediment, as for example, the collection of tooth paste or powder, from the bottom surface of the head.

In the preferred form of my invention the intersecting surfaces of the spiral grooves 11 and other portions thereof are preferably rounded so as to avoid any sharp corners in which sediment may collect. Also to this end it is preferred that the defining walls of the aperture should be smoothly finished and devoid of any dents or crevices.

Referring now to Figure 4 I have shown a modified form of my invention in which the apertures 20 formed in the head 22 are each formed by a defining wall, indicated generally at 23, lying substantially in the surface of a cone, and in which the apex of the conical defining surface is directed toward the bottom surface 24 of the head 22. As before tufts of bristles 25 are mounted in the head 22 between adjacent apertures 20, and the end portions of the conical defining walls 23 adjacent the bottom wall 24 are

flared so as to aid in directing the water upon the roots of the tufts of bristles. In this form of my invention the apertures 20 are also preferably spirally grooved as at 26 so that a rotating or swirling action is imparted to the water.

In the form of my invention shown in Figure 5 the head 30 of the brush again carries a plurality of tufts of bristles one of which is shown at 32 mounted between a pair of apertures indicated generally at 33 which extend from the top surface 34 of the head to the bottom surface 35 thereof. The apertures 33 each have a defining wall, indicated generally at 36, lying substantially in the surface of a cone which is spirally grooved as indicated at 37, and arranged so that the apex of the conical defining wall extends toward the upper surface 34 of the head. The openings of the apertures at the bottom wall 34 are flared or rounded about the peripheries thereof and toward the roots of the tufts of bristles 32 for the purpose already noted for aiding in directing the water onto the roots of the tufts of bristles for the purpose already discussed.

Reference may now be had to Figure 6 in which there is shown a tooth brush head 40 which comprises two lengthwise extending rows of tufts of bristles 42 and three lengthwise extending rows of apertures 44 which may be of any of the forms above described. In the arrangement shown in Figure 6 the two rows of tufts of bristles are arranged between adjacent rows of apertures 44.

In Figure 7 there is shown another form of tooth brush in which three lengthwise rows of bristles 45 are provided and two lengthwise extending rows of apertures 46. The apertures 46 again may be of any of the constructions above described. This arrangement of the tufts and cleansing apertures is such the rows of apertures are arranged between adjacent rows of tufts of bristles.

In the arrangement of the tufts of bristles of the two forms shown in Figures 6 and 7 it will be observed that the openings of the apertures lie on a circle which is substantially tangent to the periphery of the adjacent tufts of bristles.

In the form or arrangement of the tufts of bristles as shown in Figure 6, the lengthwise side edges of the head 48 are preferably rounded so as to facilitate capillary action of water imposed in a stream on the upper surface of the edge to project latterly inwardly from the bottom surface of the head to bathe the roots of the bristles adjacent thereto in the cleaning of the brush in the manner described.

While I have shown and described what I consider to be certain preferred embodiment of my invention it will be understood that various modifications and rearrangements may be made therein without departing from the spirit and scope of my invention.

I claim:

1. A brush comprising a head, a plurality of tufts of bristles secured in said head and extending outwardly of the bottom surface of the head, and a plurality of conical apertures extending through said head at portions thereof between adjacent tufts of bristles from the upper surface to the bottom surface of the head, and said apertures substantially throughout their entire length having the defining walls thereof spirally grooved, whereby upon disposal of water said spiral grooves serve to impart a rotating or swirling action to

the water passing through said apertures so that the water is thrown circumferentially outwardly of the apertures at the bottom surface of said head upon the roots of the tufts of bristles.

2. A brush comprising a brush head having substantially parallel upper and bottom surfaces, a plurality of tufts of bristles extending outwardly of the bottom surface of the head, a plurality of spirally grooved substantially conical apertures extending through said head between the upper and bottom surfaces thereof and at portions of said head between adjacent tufts of bristles, and said apertures at the portions thereof opening outwardly of the bottom wall of said head flaring toward the roots of the tufts of bristles, whereby upon disposal of the upper surface of said head below a stream of water, said spiral grooves serve to impart a rotating or whirling action to the water passing through said apertures, and which together with surface tension or capillary action of the water with the flaring of the apertures at the bottom surface of said head serving to bathe the roots of said tufts of bristles due to the vortex created.

3. A brush comprising, a head, a plurality of tufts of bristles secured in said head and extending outwardly of the bottom surface of the head, a plurality of apertures extending through said head at portions thereof between adjacent tufts of bristles from the top surface to the bottom surface of said head, said apertures each having the defining wall thereof lying substantially in the surfaces of a pair of cones one extending inwardly of each of the top and bottom surfaces of said head and with their apices directed toward each other, and said defining wall of each of said apertures being spirally grooved, whereby upon disposal of the top surface of said head below a stream of water the spiral grooving of said apertures prevent flow of water in a straight path therethrough and impart a rotating or whirling action to the water so that the water is thrown outwardly of the apertures at the bottom surface of said head upon the roots of the tufts of bristles.

4. The brush of claim 3 characterized by the portions of the openings of the apertures at the bottom surface of said head being formed with flared surfaces extending toward the roots of the tufts of bristles so as to utilize surface tension or capillary action of the water flowing through said apertures with the flared surfaces for further effecting the delivery of the water to the roots of said tufts of bristles.

5. A brush, comprising a head, a plurality of tufts of bristles secured in said head and extending outwardly of the bottom surface of said head, a plurality of apertures extending through said head at portions thereof between adjacent tufts of bristles from the top surface to the bottom surface of said head, each said aperture having the defining wall thereof lying substantially in the surface of a cone with the apex of the latter directed toward said bottom surface of said head, and said defining walls of said apertures being

spirally grooved, whereby upon disposal of the upper surface of said head below a stream of water, said spiral grooves serve to impart a rotating or whirling action to the water passing through said apertures so that the water is thrown outwardly of the apertures at said bottom surface of said head upon the roots of the tufts of bristles.

6. A brush comprising, a head, a plurality of tufts of bristles secured in said head and extending outwardly of the bottom surface of said head, a plurality of apertures extending through said head at portions thereof between adjacent tufts of bristles from the top surface to the bottom surface of said head, each said aperture having the defining wall thereof lying substantially in the surface of a cone with the apex of the latter directed toward said top surface of said head, and said defining walls of said apertures at said bottom surface of said head having portions flaring toward the roots of the adjacent tufts of bristles, and said defining walls of said apertures being spirally grooved, whereby upon disposal of the upper surface of said head below a stream of water, said spiral grooves serve to impart a rotating or whirling action to the water passing through said apertures, and which together with surface tension of the water with the flared portions of the apertures at the bottom surface of said head serving to throw the water outwardly upon the roots of bristles due to the vortex created.

7. The brush of claim 1 characterized by said tufts of bristles being arranged in rows extending substantially lengthwise of the head of the brush, and with the apertures being arranged in rows between adjacent rows of tufts of bristles.

8. The brush of claim 1 characterized by said tufts of bristles being arranged in three substantially lengthwise rows, and in which said apertures are arranged in two rows one between each adjacent row of said tufts of bristles.

9. The brush of claim 1 characterized by said tufts of bristles being arranged in two substantially lengthwise extending rows, and in which said apertures are arranged in substantially three lengthwise rows with one row of tuft of bristles being arranged between adjacent rows of said apertures.
